DEVICE FOR THE TRANSPORTATION OF
GOODSGaston André Elie Moreau, Boulogne-sur-Seine,
FranceApplication July 27, 1933, Serial No. 682,509
In Belgium August 5, 1932

7 Claims. (Cl. 214—1)

The present invention relates to devices for the transportation of goods both on railways and on the road, said devices being called containers and consisting essentially of boxes adapted to receive the goods and provided with means permitting of easily transferring them from one vehicle to another.

The object of my invention is to provide devices of that kind that are better adapted to meet the requirements of actual practice, especially concerning the facility of transshipment, and the fixation of the container to the vehicle for transportation.

To this effect, according to my invention, in order to tranship the containers from one vehicle to another one, for instance from a railway truck to a lorry or inversely, instead of making use of rails permanently fixed to said vehicles, I provide on each of said containers, several detachable rail elements such that, during the transportation, the container may rest on at least two of them, the other elements being secured on certain faces of the container, and that, when the container is to be transshipped from one vehicle to another, these other elements may be brought into line with the first mentioned ones so as to permit of moving the container from one vehicle to the other along the rails thus assembled.

Other features of my invention will appear from the following detailed construction.

Preferred embodiments of my invention will be hereinafter described with reference to the accompanying drawings given merely by way of example, and in which:

Figs. 1 and 2 are elevational views at right angles to each other showing a container according to my invention provided with means for permitting its easy transshipment from one vehicle to another;

Fig. 3 is an elevational view, partly in section, of a coupling device carried by the rail elements that serve to the transshipment, according to my invention;

Fig. 4 is a partial view, partly in section, of another embodiment of this coupling device;

Figs. 5 and 6 show in elevational and plan view respectively, a device for securing the rail elements to the container according to my invention;

Figs. 7 to 11 are diagrammatic elevational views showing the whole of a railway truck, a motor lorry and a container according to my invention, in five different relative positions suc-

cessively occupied by the frame with respect to the two vehicles during the transshipment.

According to my invention, the container is made in the usual manner of a box, which may or not be capable of being taken to pieces, of a substantial parallelepipedic shape, for instance substantially cubic, and provided with means for facilitating its transshipment as will be herein-after described.

Up to this time, said means were of two kinds: 10 Either one made use of improved hauling apparatus of a very expensive kind, and with which accordingly railway stations of small importance could not be equipped, or the railway cars and lorries were provided with rails fixed thereto in 15 a stationary manner so that the containers could be moved along said rails for transshipping them.

The latter solution is not better than the first because, on the one hand it requires a special 20 equipment of the railway cars and of the lorries which involves difficulties of exploitation and is very expensive, and on the other hand it makes it necessary, for the transshipment, to place the lorry in a well determined position with respect 25 to the railway car, so that the respective rails may be brought in exact register, which constitutes a difficult and long operation.

According to my invention, and in order to avoid these many drawbacks, I combine with 30 each container a certain number of detachable rail elements. These rail elements are so arranged that, on the one hand, while the container is being transported on a vehicle, either a railway car or a lorry, said container may rest 35 on at least two of said rail elements, while at least some of the other elements can be secured to certain faces of the container. On the other hand, when the container is being transferred from one vehicle to the other, these other elements are brought in line with the first ones so 40 as to permit of transferring the container onto the second vehicle along the rail track thus constituted.

Preferably these elements are so arranged that 45 they can be connected together by detachable coupling means so that it is possible to assemble them as well in their positions for transportation, as in their positions for transshipment.

To this effect, said rail elements may for 50 instance be made in the following manner:

Three pairs of rail elements of the kind above referred to are provided, as follows:

On the one hand there are provided two pairs 55 of rails a^1, a^2 of equal length, said length being

so chosen that one or the other of these two pairs can support container *b* during transportation on one of the vehicles, said container then resting on said pair of rails through two series of rollers *c* being carried along sectional irons *d* rigidly fixed to the bottom of said container; the two rails that support the container are disposed either at right angles to the longitudinal axis of the car, when the container is carried by the railway car, or parallelly to the longitudinal axis of the lorry and substantially at equal distance from said axis when the container has been transshipped to a lorry.

On the other hand a third pair of rails *e*, both of a length either equal to that of rails *a*¹, *a*² or different therefrom, for instance smaller than it is shown in the drawings given by way of example, is to be utilized for transshipment as a connection between the two pairs of rails *a*¹ and *a*² respectively placed on the floor of the car and on that of the lorry (Figs. 8 to 10).

The rails can be of any suitable kind, but it is advantageous to make them hollow so as to reduce their weight. They may for instance consist, as shown in the drawings of U-shaped sectional irons provided with lateral flanges, the open portion of the U being closed by a plate applied against said flanges and of a relatively great width, so as to distribute their weight over a greater surface of the floor of the car or of the lorry, and also to improve stability.

As for the means for assembling together said rails, they are made in such manner that one of the above mentioned pairs can be assembled indifferently to any of the two other pairs. I accordingly make use of jointed and removable coupling means, each rail being provided to this effect for instance with a male coupling element *f*¹ and a female coupling element *f*² at both of its ends respectively.

Said jointed and detachable coupling means can be made in any suitable manner, for instance by utilizing a cotter *g* adapted to be inserted in holes provided in said male and female coupling elements (Fig. 3). This cotter is kept in position by suitable locking means such as a key *i*, pivoted for instance about a pin *j* within a corresponding cavity *j* provided in said cotter. With this arrangement cotter *g* can be removed only when key *i* is brought into a direction parallel to the axis of said cotter *g*.

Of course I do not wish to be limited to this embodiment of the coupling means, and I have shown in Fig. 4 another embodiment of suitable coupling means. According to this embodiment, cotter *g* is permanently fixed to the female coupling element *f*², and it is provided with flat faces so that it is possible to introduce said cotter into the corresponding hole *h* of the male coupling element, by causing said flat faces to pass between corresponding flat surfaces *h*¹ of coupling element *f*¹. The corresponding rails are then pivoted with respect to each other so as to bring them into their respective positions of utilization.

With the arrangement shown in Fig. 4, it suffices, in order to introduce cotter *g* into hole *h* to dispose the rails to be assembled in such manner that their axes make with each other an angle of 45°.

Advantageously, rails *e* will be given a height smaller than that of rails *a*¹, *a*² in order that, when the rails are assembled for transshipment (Figs. 8 to 10) and the horizontal surfaces of the railway car and of the lorry are disposed at

different levels, rails *e* could not, if they are somewhat slightly inclined for this reason, butt against the edges of the floor of the railway car or of the lorry.

With the device that has just been described, there are provided on four lateral faces of the container or at least on two lateral parallel faces thereof, fixation means for locking the container with respect to the pair of rails, for instance *a*¹, on which it rests for transportation on the railway car or on the lorry. To this effect the two rails *a*², which are coupled to the pair of rails *a*¹ through cotters *g*, are fastened to the corresponding lateral face of the container by means of suitable fixation means, this system being such that the container is perfectly secured to the vehicle by which it is transported. The fixation means above referred to comprise for instance a plate *k* rigidly connected to the container, two threaded rods *l*, a cross member *m* and two levers *n* provided with screw threaded holes adapted to engage on said rods *l* (Figs. 5 and 6).

To facilitate transportation and in order to still improve the fixation of container *b* with respect to rails *a*¹ on which its rests, rails *e* will advantageously be fastened to the corresponding lateral face of the container by means of fixation devices such as those just above described, the ends of said rails *e* being connected to rails *a*¹ by cotters *g*.

These fixation means will then be so made that they can cooperate as well with rails *a*¹ or *a*² as with rails *e*, which are of shorter length. Of course I do not wish to be limited to these fixation means.

In the preceding description, it has been assumed that the rollers *c* through which the container slides on the rails, are carried by said container. But it is obvious that these rollers can be supported by the groups of rails *a*¹, *a*², *e*. In this case, transshipment will be performed by causing sectional irons integral with the bottom of the container or rigidly fixed thereto to slide over said rollers, when said group of rails have been assembled. These rollers may also be replaced by cylinders.

When rollers are utilized they can be either of the grooved type or of the railway car wheel type.

According to another embodiment of my invention, relating to the case in which rollers are used, said rollers may be disposed not under the container but laterally thereto, in which case those of the rails *a*¹, *a*², *e* that are intended to be fixed on the lateral faces of the container, would be secured not on the faces at right angles to the direction in which transshipment is effected, but on the faces parallel to this direction.

According to my invention, I obtain a device which works in the following manner:

Supposing first for instance that the container is on a railway car, it rests on a pair of rails *a*¹ disposed at right angles to the longitudinal axis of the car. In the position of transportation this pair of rails *a*¹, is assembled by means of cotters *g* with the two other pairs of rails *a*² and *e* which, as above explained, are fixed to the corresponding faces of the container thus making an angle of 90° with rails *a*¹. When it is desired to transship the container to a lorry, the latter is driven backwards at right angles to the railway car and substantially opposite container *b*. The levers *n* that fix rails *a*² are slightly unscrewed. Cross members *m* are swung aside, and rails *a*²

can then be detached and placed on the floor of the lorry. The levers *n* that fix rails *e* are then unscrewed and the corresponding cross members *m* are swung aside. If the lorry is located opposite rails *e*, the latter are then flapped back against the floor of the lorry (Fig. 7), the latter being supposed to be at a suitable distance from the railway car.

If the lorry is located on the opposite side, cotters *g* are removed and rails *e* are transferred to the opposite side, being assembled to the ends of rails *a¹* that were previously connected with rails *a²*.

Rails *a²* are then fixed in line with rails *e* by means of cotters *g*, which are now available.

Rails *e* thus form a bridge across the space between the railway car and the lorry.

Container *b* is then caused to run successively along rails *a¹*, rails *e* and rails *a²*.

Container *b* is now located on the lorry, on the floor of which it rests through rails *a²*. As rails *e* and *a¹* are now free, they can be fixed on to the container in the manner above described, rails *a¹* occupying the place previously occupied by rails *a²*.

If necessary, the whole of rails *a¹*, *a²*, *e* can be strengthened by cross pieces during transshipment. It will readily be understood that such a device makes it possible to do away with all the drawbacks above pointed out, since it makes it possible to utilize railway cars and lorries that have no special equipment, and it does not necessitate a very great accurateness of the respective positions of the railway car and of the lorry during the transshipment.

Of course this device can be combined with a mechanism of any suitable kind for actuating rollers *c* during transshipment.

My device can also be utilized for transferring a container from one railway car to another railway car, the two cars being then disposed either in line with each other, or parallel to each other (the rails *a¹* that support the container being in each case disposed in a suitable direction with respect to the axis of the car). In a likewise manner, the device could be used for transshipping the container from a railway car to a lorry by bringing such lorry in parallel position with respect to the car. It might also be used for unloading containers from a railway car or from a lorry, to the ground.

While I have described what I deem to be practical and efficient embodiments of my invention, it should be well understood that I do not wish to be limited thereto as there might be changes made in the arrangement, disposition and form of the parts without departing from the principle of my invention as comprehended within the scope of the appended claims.

What I claim is:

1. A device for the transportation of goods and their transshipment from one vehicle to another, which comprises in combination, a container adapted to receive said goods, a plurality of rail elements associated with said container in such manner that there is always at least one pair of them that supports said container, means for removably and interchangeably securing the other rail elements to the container, and coupling means for assembling said rail elements in line with one another, whereby the container can be caused to move along the trackway thus constituted from the pair of rail elements on which it rested to

another pair of rail elements placed on the vehicle to which it is to be transshipped.

2. A device for the transportation of goods and their transshipment from one vehicle to another, which comprises in combination, a container adapted to receive said goods, a plurality of rail elements associated with said container in such manner that there is always at least one pair of them that support said container, means for removably and interchangeably securing the other rail elements to the container, and removable coupling means for either connecting with the rail elements that support the container the other rail elements when they are fixed to the container or assembling all the rail elements at the end of one another, whereby the container can be caused to slide along the trackway thus constituted from the pair of rail elements on which it rested to another pair of rail elements placed on the vehicle to which the container is to be transshipped.

3. A device for the transportation of goods and their transshipment from one vehicle to another, which comprises in combination, a container adapted to receive said goods, a plurality of rail elements associated with said container in such manner that there is always at least one pair of them that slidably supports said container, a plurality of rollers carried by the under face of said container and adapted to run along said rail elements, means for removably and interchangeably securing the other rail elements to the container, and coupling means for assembling said rail elements in line with one another so that the container can be caused to slide along the trackway thus constituted from the pair of rail elements on which it rested to another pair of rail elements placed on the vehicle to which it is to be transshipped.

4. A device for the transportation of goods and their transshipment from one vehicle to another, which comprises in combination, a container adapted to receive said goods, a plurality of rail elements associated with said container in such manner that there is always at least one pair of them that supports said container, a plurality of rollers interposed between the under face of said container and the last mentioned rail elements, means for removably and interchangeably securing the other rail elements to the container, and removable coupling means for either connecting with the rail elements that support the container the other rail elements when they are fixed to the container or assembling all the rail elements at the end of one another, whereby the container can be caused to slide along the trackway thus constituted from the pair of rail elements on which it rested to another pair of rail elements placed on the vehicle to which the container is to be transshipped.

5. A device for the transportation of goods and their transshipment from one vehicle to another, which comprises in combination, a container adapted to receive said goods, two interchangeable pairs of rails of equal length one of which always supports the container, a plurality of rollers interposed between said container and the last mentioned pair of rails, means for removably fixing the other pair of rails to one face of the container, a third pair of rails, means for removably fixing the last mentioned pair of rails to one face of the container, and coupling

- means for assembling the three pairs of rails in line, whereby the container can be caused to slide along the trackway thus constituted from the pair of rails on which it rested to another pair of rails placed on the vehicle to which the container is to be transshipped.
6. A device for the transportation of goods and their transshipment from one vehicle to another, which comprises in combination, a container adapted to receive said goods, two interchangeable pairs of rails of equal length one of which always supports said container, a plurality of rollers carried by the under face of said container and interposed between said container and the last mentioned pair of rails, means for removably fixing the other pair of rails to one face of the container, a third pair of rails of shorter length, means for removably fixing the last mentioned pair of rails to another face of the container, and removable coupling means for either connecting with the rails that support the container the two other pairs of rails when they are fixed to the container or assembling all the rail elements at the end of one another, whereby the container can be caused to slide along the trackway thus constituted from the pair of rails on which it rested to another pair

of rails placed on the vehicle to which the container is to be transshipped.

7. A device for the transportation of goods and their transshipment from one vehicle to another, which comprises in combination, a container adapted to receive said goods, two interchangeable pairs of rails of equal length one of which always supports said container, a plurality of rollers carried by the under face of said container and interposed between said container and the last mentioned pair of rails, means for removably fixing the other pair of rails to one face of the container, a third pair of rails of shorter length, means for removably fixing the last mentioned pair of rails to another face of the container, and removable coupling means for either connecting with the rails that support the container the two other pairs of rails when they are fixed to the container or assembling all the rail elements at the end of one another, whereby the container can be caused to slide along the trackway thus constituted from the pair of rails on which it rested to another pair of rails placed on the vehicle to which the container is to be transshipped.

GASTON ANDRÉ ELIE MOREAU.
